UNITED STATES PATENT OFFICE.

ALFRED H. HUMPHREY, OF NEW YORK, N. Y.

GAS-BURNER.

1,245,346.

Specification of Letters Patent. Patented Nov. 6, 1917.

Application filed June 10, 1916. Serial No. 102,905.

To all whom it may concern:

Be it known that I, ALFRED H. HUMPHREY, a citizen of the United States, residing at the city, county, and State of New York, have invented certain new and useful Improvements in Gas-Burners, of which the following is a specification.

This invention relates to improvements in gas burners.

10 My improved gas burner is particularly designed by me and is especially well adapted for use in heating devices of the radiant type, for example, such as is shown in my application for Letters Patent, filed May 18, 15 1916, Ser. No. 98,337, although my improvements are desirable and readily adapted for use in various relations where high temperature flames are particularly desired.

The main objects of my invention are:

20 First, to provide an improved gas burner adapted to produce a high temperature flame.

Second, to provide an improved gas burner adapted to produce a high temperature 25 flame without back firing, the burner tube below the tip being unobstructed.

Third, to provide an improved gas burner capable of burning a large quantity of gas and of producing a flame of high temperature 30 without "streaming."

Fourth, to provide an improved gas burner which is practically noiseless, even when consuming gas under high pressure.

Fifth, to provide an improved gas burner 5 having very efficient combustion of the gas.

Sixth, to provide an improved gas burner which is simple and very durable in structure.

Further objects, and objects relating to 40 structural details, will definitely appear from the detailed description to follow.

I accomplish the objects of my invention by the devices and means described in the following specification. The invention is 45 clearly defined and pointed out in the claims.

A structure which is a preferred embodiment of my invention is clearly illustrated in the accompanying drawing, forming a 50 part of this specification, in which:

Figure I is a rear perspective view of a burner embodying the features of my invention, a portion of the Bunsen tube being broken away.

55 Fig. II is a detail view, partially in sec-

tion, on a line corresponding to line 2—2 of Fig. I, showing my improved burner installed in a gas heating device of the radiant type.

Fig. III is a plan view of one of my improved burner tubes.

Fig. IV is a detail vertical section thereof on a line corresponding to line 4—4 of Fig. III.

Fig. V is a plan view of a slightly modified form of my improved burner tube, the modification being in the shape of the tip.

Fig. VI is a detail plan view of another modified form of my improved burner tube, the modification being in the shape of the 70 tip.

In the drawing, similar reference characters refer to similar parts throughout the several views, and the sectional views are taken looking in the direction of the little 75 arrows at the ends of the section lines.

Referring to the drawing, the body of my improved burner comprises a top wall 1, side walls 2 and 3, the wall 2 being the front wall and the wall 3 being the rear wall, and a bottom wall 4. The top wall is flat and the side walls are uniformly spaced. The bottom wall 4 is inclined upwardly toward each end providing a gas chamber of 80 decreasing capacity toward the ends of the 85 body.

The supply pipe 5 is disposed longitudinally of the body and provided with an elbow 6 joined to the side wall 3 so that the pipe 90 delivers to the chamber centrally and at right angles to the side walls thereof. The advantage of this is that it secures a substantially even distribution of the gas within the chamber to the several burner tubes 95 mounted thereon.

The Bunsen tube 7 is provided with the usual air inlets 8. The gas delivery nozzle is not shown as its relation to the Bunsen tube will be readily understood.

The body is provided with attaching ears 100 9 at its ends having holes 10 adapted to receive the attaching screws. The burner tubes 11 are threaded into the top 1 of the body.

These burner tubes 11 are preferably rectangular at the tip, as shown in Figs. III, IV 105 and V, which differ slightly in shape. The tubes are provided with uniformly spaced vertical slits 12 in opposite walls adapted to receive the flat bars 13, which are arranged in the slits and welded or brazed in position 110

so that they have a heat conducting union or joint with the walls of the tube. The spaces 14 between these bars constitute unobstructed slot-like jet apertures extending across the tip. The bars are of uniform cross section from end to end, so that the jet apertures are also of uniform cross section from end to end.

I find in practice that very satisfactory results are secured where the thickness of 10 the bars is substantially that of the jet apertures and the depth of the bars approximately four times the width of the jet apertures. The maintaining of the proper relative proportion in depth and thickness of 15 the bars relative to the jet apertures is of advantage in securing the best results, that is, as when properly proportioned, no additional means are required to prevent back 20 firing, the burner tubes being entirely unobstructed below the tips and, further, the gas burns quite close to the surface of the tips and without "streaming," even under 25 relatively high pressures. A further advantage of this arrangement is that the structure is practically noiseless.

The bars being effectively united with the 30 walls of the tube to form heat conducting joints or unions therewith the heat is conducted away so that they do not become excessively heated so as to destroy them or to cause back firing.

I preferably use a non-corrodible metal 35 and one not affected by considerable temperatures, such as certain alloys of nickel and iron.

I have shown my improved burner in Fig. 40 II in operative relation in a heating stove or device of the radiant type, the structure there illustrated being substantially that of my application above referred to in which the radiants 15 are supported on the base 16 above the burner tubes. The base has openings 17 therein below the radiants.

In heating devices of this character it is 45 of primary importance that the radiating elements be brought to a highly heated state and as the cross section of the radiants is small it is necessary that the burners below them be highly efficient.

My improved burner is especially designed, as stated, for use in this relation. It is also necessary in devices of this type that the gas shall be evenly distributed to 50 the various burner tubes or tips and my improved burner is also especially designed to accomplish that end.

With my improved burner a sufficient 55 quantity of combustible mixture is passed without noise and is so distributed that an even flame of exceedingly high temperature is produced and very perfect combustion of the gas secured.

As stated, the necessity for screens or the 60 like within the tubes is overcome, which is

of advantage, as such screens choke the flow of the gas and, further, collect foreign substances, such as lint and the like, requiring the cleaning of the burner at frequent intervals. Any foreign matter that passes into my improved burner has unobstructed passage to the tips where it is consumed.

It is found in practice that with gas at 65 normal pressures delivered by the gas mains of the average city satisfactory results 70 may be secured if the jet apertures are between the limits of twenty and forty thousandths of an inch, the bars being of substantially the same thickness as the width of the apertures and the depth of the bars approximately four times the width of the apertures.

With the rectangular tips it is easily possible to secure uniformity. By slotting the 75 tips and inserting the bars and brazing or welding them in place as described, satisfactory joints are formed between the bars and the walls so that the heat is readily conducted from the bars to the walls and dissipated, thus preventing over heating of the 80 bars which might induce back firing or destroy or warp the bars. By this method of manufacture the burners may be economically produced and the bars may be of different material from the tubes.

I have not attempted to illustrate or describe various other modifications than those illustrated and which I might contemplate or which might be desirable to adapt my improvements to various uses, as I believe 90 the disclosure made will enable those skilled in the art to which my invention relates to embody or adapt the same as conditions may require.

Having thus described my invention, what 95 I claim as new and desire to secure by Letters Patent, is

1. A gas burner comprising a metal burner tube rectangular at the tip and having vertical uniformly spaced slits in opposite walls thereof, and metal bars of uniform cross section disposed in said slits and united to the walls to provide heat conducting unions therewith, the spaces between the bars constituting unobstructed slot-like jet apertures of substantially uniform cross section from end to end, the thickness of the bars being substantially that of the jet apertures, the depth of the bars being approximately 10 four times that of the jet apertures.

2. A gas burner comprising a metal burner tube rectangular at the tip and having uniformly spaced slits in opposite walls thereof, and metal bars of uniform cross section disposed in said slits and united to the walls 11 of the tube to provide heat conducting unions therewith, the spaces between said bars constituting unobstructed slot-like jet apertures of uniform cross section extending across the tip, the depth of the bars being sub- 12

stantially greater than the width of the jet apertures, the thickness of the bars being substantially that of the jet apertures.

3. A gas burner comprising a metal burner tube rectangular at the tip and having uniformly spaced slits in opposite walls thereof, and metal bars of uniform cross section disposed in said slits and united to the walls of the tube to provide heat conducting unions therewith, the spaces between said bars constituting unobstructed slot-like jet apertures of uniform cross section extending across the tip. 35

4. A gas burner comprising a burner tube, and bars disposed in a uniformly spaced relation across the tip and united to the walls of the tube to provide heat conducting unions therewith, the spaces between said bars constituting slot-like jet apertures of uniform 20 cross section extending across the tip, the depth of the bars being substantially greater than the width of the jet apertures, the thickness of the bars being substantially that of the jet apertures.

25 5. A gas burner comprising a metal burner tube having opposed slits in the walls thereof, and metal bars disposed in said slits and united to the walls to provide heat conducting unions therewith, the spaces between 30 said bars constituting unobstructed slot-like

jet apertures of uniform cross section extending across the tip, the depth of the bars relative to the width of the jet apertures being such as to prevent back firing therethrough, the tube being unobstructed below the bars. 35

6. A gas burner comprising a metal burner tube having opposed slits in the walls thereof, and metal bars disposed in said slits and united to the walls to provide heat conducting unions therewith, the spaces between said bars constituting unobstructed slot-like jet apertures of uniform cross section extending across the tip. 40

7. A gas burner comprising a burner tube, and bars disposed in a uniformly spaced relation across the tip, the spaces between said bars constituting slot-like jet apertures of uniform cross section extending across the tip, the depth of the bars relative to the width of the jet apertures being such as to prevent back firing through the apertures, the tube being unobstructed below the bars. 50

In witness whereof, I have hereunto set my hand and seal in the presence of two 55 witnesses.

ALFRED H. HUMPHREY. [L. S.]
